BEVERAGE COOLING APPARATUS

Delbert F. Newman, Schenectady, N. Y., assignor
to General Electric Company, a corporation of
New York

Application November 5, 1932, Serial No. 641,391

3 Claims. (Cl. 62—143)

My invention relates to apparatus for cooling bottled beverages from which the bottles can be conveniently dispensed.

It is an object of my invention to provide a simple and compact cooling apparatus for bottled beverages and the like from which the bottles may be easily removed or placed therein.

Further objects and advantages of my invention will become apparent as the following description proceeds and the features of novelty which characterize my invention will be pointed out with particularity in the claims annexed to and forming a part of this specification.

For a better understanding of my invention, reference may be had to the accompanying drawing in which Fig. 1 is a side elevation, partly in section, of a beverage cooler constructed in accordance with my invention; Fig. 2 is a top view of the beverage cooler shown in Fig. 1; and Fig. 3 is a detailed view of the evaporator and float valve construction employed in the beverage cooler of Fig. 1.

In accordance with my invention, I provide a unitary structure comprising a hollow stand supporting a thermally insulated cooling chamber, and provided with a readily removable cover, an evaporator within the chamber surrounded by water or brine for cooling articles placed therein, and a compressor-condenser unit supported within the hollow stand and arranged to supply refrigerant to the evaporator.

Referring now to Fig. 1, I have shown a sheet metal stand 10 supporting a thermally insulated cooling chamber 11, which comprises a tank 12 containing suitable liquid, and a cylindrical casing 13 spaced from the tank 12 and provided with suitable insulation 14 therebetween. The bottom of the tank 12 is insulated by a plurality of pressed sheets 15. The cooling chamber 11 is closed at the top by two semi-circular lids 16 and 17, hinged back to back and fitting in a circular opening in a frame 18 which is secured on top of the side wall of the chamber 11. These lids are freely rotatable in the frame so that any bottle in the cooler can be easily removed or replaced. The cooling chamber is rigidly secured to the stand 10 by a flanged base 19 secured to the casing 13 and to the top of the stand 10 by welding, or in any other suitable manner.

In order to evenly cool the liquid in the tank 12 I provide a hollow evaporator 20 of the flooded type in the center of the tank. This evaporator, as shown in Fig. 3, is formed by two interfitting inner and outer cylindrical shells 21 and 22, respectively. These shells are sealed together on a

ring 23 at the top, and at the bottom by a fluid tight joint 24. The inner shell 21 is provided with a flange 25 which is bolted to the tank 12 to hold the evaporator in place. A metal ring 26 and gaskets 27 and 28 are provided to form a fluid-tight joint between the evaporator and the bottom of the tank. A float valve 29 is arranged within the evaporator 20. Liquid refrigerant is supplied to the float valve through a conduit 30 and flows from the float valve to the evaporator 10 through conduit 31. Gaseous refrigerant is withdrawn from the evaporator through conduit 32. These conduits pass through the bottom of tank 12 and retained in place by a spacing block 33. Conduits 30 and 32 are preferably covered with 15 insulating tubing 34. The space remaining around the float valve and conduits is filled with insulation 35, and the opening at the top is closed by flanged plate 36 which is clamped between 20 rings 23 and 37 by bolts 38, a gasket 39 being provided to form a fluid tight seal. A rack 40 is provided on the bottom of the tank 12 to support bottles or other articles above the same, and a protecting frame 41 surrounds the evaporator and insures free circulation of the cold water or brine 25 in the tank about the articles in the tank.

Within the stand 10 below the cooling chamber 11 is arranged a compressor-condenser unit 42 for supplying liquid refrigerant to the evaporator 20. This unit is supported within the stand 10 on a 30 frame 43, and comprises a steel casing 44 having, a motor and a compressor therein and a coiled tubular condenser 45 supported on the casing 44 in spaced relation thereto. Refrigerant is compressed by the compressor inside of the casing 35 44 and flows into the condenser 45 where it is liquefied and then is forced up through conduit 30 to the float valve 29. After the liquid refrigerant has been evaporated it is drawn back to the compressor through the suction conduit 32. 40

In the operation of the beverage cooler described the tank 12 is filled with water or a brine solution up to about the top of the evaporator 20. The water or brine in the tank is cooled by the evaporator and circulates about the bottles or other articles and cools them. Any portion of the tank can be readily reached through the doors 16 and 17 and any article may be removed or added without interfering with the articles 45 already on the rack 40.

What I claim as new and desire to secure by Letters Patent of the United States is:

1. A cooling apparatus for bottled beverages and the like including a supporting frame, a thermally insulated tank supported on said frame, a

refrigerant evaporator arranged within said tank, means including a float valve arranged within and insulated from said evaporator for controlling the flow of refrigerant to said evaporator, and means supported within said frame for supplying liquid refrigerant to said float valve and for withdrawing gaseous refrigerant from said evaporator.

2. A cooling apparatus for bottled beverages and the like including a supporting frame, a thermally insulated tank supported on said frame, a circular cover for said tank, said cover comprising two sections hinged together and being rotatable on said tank, a refrigerant evaporator arranged at the center of said tank, and means

supported within said frame for supplying liquid refrigerant to said evaporator and for withdrawing gaseous refrigerant from said evaporator.

3. A cooling apparatus for bottled beverages and the like including a thermally insulated tank containing a liquid, a hollow evaporator immersed in said liquid and secured by a fluid-tight joint to the bottom of said tank, means including a flow controlling device arranged in said evaporator and insulated therefrom for supplying refrigerant thereto, and means including a connection inside of said evaporator for withdrawing vaporized refrigerant therefrom.
